UNITED STATES PATENT OFFICE.

ANTOINE T. BOUSQUET, OF WORCESTER, MASSACHUSETTS.

ROLL-PAPER STARTER.

1,249,311.

Specification of Letters Patent. Patented Dec. 11, 1917.

Application filed November 15, 1916. Serial No. 131,557.

To all whom it may concern:

Be it known that I, ANTOINE T. BOUSQUET, a citizen of the United States, residing at Worcester, in the county of Worcester and 5 State of Massachusetts, have invented a new and useful Roll-Paper Starter, of which the following is a specification.

This invention relates to a device to be used in connection with a cutter bar for cutting or tearing sheets of paper from a roll, particularly of that type used in stores and 10 markets for wrapping paper.

The principal objects of this invention are to provide a simplified form of starter which 15 will be held yieldingly against the roll in such a way that no matter whether the roll is small or large it will effectively start the edge of the paper so that it can be reached by the fingers and torn off. I am aware of 20 the fact that several have been invented for the same general purpose, but this invention is designed to secure more efficient results in a more simple way and especially to provide an arrangement which will necessarily always 25 work.

Reference is to be had to the accompanying drawings, in which—

Figure 1 is a front elevation of an ordinary type of paper cutter with a preferred 30 form of this invention applied thereto; and

Fig. 2 is a perspective view of the same showing how the paper is started by it.

The drawings show the invention applied to a cutter which is of ordinary character 35 and is mounted on a frame 10 by means of pivotal supports 11. These pivotal supports are provided with springs 13 coiled on them and having their ends attached in the usual way to press the cutter bar against the roll 40 yieldingly and keep it there as the roll decreases in size. The cutter bar 14 is of spring steel and extends beyond the end of the roll.

This invention relates to a starter shown 45 in the form of a sheet metal member 15 of U-shaped construction having one of its legs provided with a cylindrical passage at 16 formed by bending up the end of the leg and adapted to receive one of the supports 50 11 so that the starter is pivoted on a vertical axis above the cutter bar, and is supported thereby. The end of the cutter bar presses against the vertical portion of the starter and presses it back against the roll of paper.

In this way the upper leg of the starter is 55 kept in contact with the roll and also the inner end of the lower leg. This inner end is provided with a wedge shaped toe 17 which projects upwardly and as it presses closely against the roll it necessarily always 60 separates the end of the web as shown in Fig. 2 and thus performs its function effectually.

It is to be noted that this starter is held 65 freely on the cutter bar when there is no roll of paper in position, but that it is pressed against it both by the springs 13 and the spring provided by the end of the cutter bar itself. In this way the separating toe is 70 always kept in the proper position to perform its work.

Although I have illustrated and described only a single form of the invention I am aware of the fact that modifications can be made therein by any person skilled in the 75 art without departing from the scope of the invention as expressed in the claims. Therefore I do not wish to be limited to all the details of construction herein shown and described, but what I do claim is:—

1. In a paper serving apparatus, the combination with the frame rotatably supporting the roll of paper, of a resilient cutter bar, a support for said bar pivoted on said frame and having arms carrying the bar, a 80 paper-edge starter pivotally mounted on one arm of said support, one end of said bar pressing said starter against the cylindrical surface of the roll, and a toe on said starter adapted to underlie the cut edge of the 85 paper.

2. In a roll paper serving apparatus, the combination with the frame supporting the paper roll, of a resilient cutter or tearing bar 90 extending throughout the length of the roll, pivoted supports for said bar carried by said frame, springs interposed between the latter and said supports to press said bar against the roll, a U-shaped paper starter pivotally mounted on an arm of one of said supports, 95 the end of said bar pressing said starter against the roll both above and below said bar, and a wedge-shaped toe on said starter below said bar adapted to underlie the cut edge of the paper.

In testimony whereof I have hereunto affixed my signature.

ANTOINE T. BOUSQUET.
